US0D1033823S

(12) **United States Design Patent** (10) **Patent No.:** **US D1,033,823 S**
(45) **Date of Patent:** **** Jul. 9, 2024**

(54) **SHOE**

(71) Applicant: **adidas AG**, Herzogenaurach (DE)

(72) Inventor: **Gregor McWee**, Portland, OR (US)

(73) Assignee: **adidas AG**, Herzogenaurach (DE)

(**) Term: **15 Years**

(21) Appl. No.: **29/805,996**

(22) Filed: **Aug. 31, 2021**

Related U.S. Application Data

(63) Continuation of application No. 29/703,992, filed on Aug. 30, 2019, now Pat. No. Des. 930,963, which is a continuation of application No. 29/632,662, filed on Jan. 9, 2018, now Pat. No. Des. 863,743.

CLAIM

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the shoe that form no part of the claimed design.

1 Claim, 6 Drawing Sheets
